DESIGN FOR A COAT

Charles Salerno, New York, N. Y.

Application June 21, 1941, Serial No. 101,586

Term of patent 3½ years

To all whom it may concern:

Be it known that I, Charles Salerno, a citizen of the United States of America, residing in New York city, county of New York, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

Fig. 3 is an enlarged view of the pocket portion illustrating the applique trimming.

I claim:

The ornamental design for a coat, substantially as shown.

CHARLES SALERNO.
